UNITED STATES PATENT OFFICE.

ALVIN E. COBB, OF DES MOINES, IOWA.

PRICE-CARD DEVICE.

Application filed July 5, 1927. Serial No. 203,509.

The object of my invention is to provide a price card device of simple, durable and inexpensive construction, that may be readily, quickly and easily attached to or removed 5 from the front edge of a shelf, and to provide price cards and face plates detachably connected with the device, and so arranged that by readjusting the positions of the cards and face plates a great variety of price 10 marks may be displayed in a neat and attractive manner from the front of the device, and whereby all of the price cards and face plates may be contained in the device after such readjustment of the price cards 15 and face plates to make a self-contained unitary price card device, thus avoiding danger of losing or misplacing the detachable parts.

My invention consists in the construction, 20 arrangement and combination of the various parts of the device, whereby the objects contemplated are attained, as hereinafter more fully set forth, pointed out in my claim, and illustrated in the accompanying drawings, in which:

Figure 1 shows a perspective view illustrating a portion of a shelf with my improved price card device applied thereto, a portion of the face plate being broken away 30 at the top to show the adjacent edges of the price cards in the rear of the face plate.

Figure 2 shows an enlarged, detail, sectional view on the line 2—2 of Figure 1.

Figures 3 and 4 illustrate respectively the 35 outer and inner surfaces of one of the face plates.

Figures 5 and 6 are similar views of another of a series of face plates.

Figures 7 and 8 are similar views of a 40 third face plate.

Figures 9 and 10 show the front and rear faces respectively of one of the price cards.

Figures 11 and 12 show the front and rear faces respectively of another of the price 45 cards.

Figures 13 and 14 show the front and rear faces of another of the price cards.

Figures 15 and 16 show the front and rear faces of the remaining price card.

50 Referring to the accompanying drawings, I have used the reference numeral 10 to indicate the front or body portion of the holder. The holder is preferably made complete of a single piece of sheet metal and 55 the top edge of the front 10 is bent rearwardly at 11 and is designed to rest upon

the top of a shelf. The side edges of the front 10 are extended straight forwardly at 12 and then inwardly toward the vertical center of the holder at 13, substantially parallel with the front 10. The bottom edge is projected forwardly at 14 and upwardly at 15. In the central portion of the front 10, a part thereof is cut at its top and sides to form a tongue 16, which may be bent 60 rearwardly, as shown in Figure 2, to yieldingly engage the bottom of the shelf 17, to thereby more firmly hold the card holder in position.

By this arrangement it will be seen that 70 the front portion of the holder, which lies adjacent to the front edge of the shelf is formed with marginal portions turned inwardly, and which form slots at the sides and bottom for the reception of the cards, 75 the top being open so these cards may be readily removed.

The price cards proper are indicated generally by the numeral 18 and are preferably squared and made of rather thick paper or 80 similar material. It is necessary to use four of these cards, and the outer dimensions of two cards 18 are such that they may be readily placed in the slots in the margin of the holder from above and their inner edges 85 will loosely engage each other, and the two cards will stand in the same plane. The price card illustrated in Figures 9 and 10 has marked upon one face thereof at the left side the numeral 0, and at the right side 90 the numeral 9, and between the two the word "Left" in small letters. The opposite face, as illustrated in Figure 10, is blank. Another card has printed upon one face thereof the numeral 9 at the right side, the 95 numeral 0 at the left side and the word "Right" in the space between them. Its opposite side is blank, as shown in Figure 12.

The third card, as shown in Figure 13 has printed on one face the word "Right" in 100 the center, and at the top the numeral 8, at the bottom the numeral 6, at the right side the numeral 7 in inverted position, and at the left side the numeral 5. On its opposite face, shown in Figure 14, there is at the left 105 side the numeral 1, at the bottom the numeral 2, at the right side the numeral 3 in inverted position, and at the top the numeral 4, and the word "Right" at its central portion. The remaining price card has at its 110 right side, the numeral 5, at its left the numeral 7 in inverted position, at its top the

numeral 8, and at its bottom the numeral 6, and the word "Left" in its central portion. On the opposite side at the right is the numeral 1, at the bottom the numeral 2, at the left the numeral 3 in inverted position, and at the top the numeral 4.

The numerals printed upon these cards are so arranged that only the two that are on the sides thereof adjacent to the meeting edges of the cards may be viewed when in use, and these numerals are, therefore, all printed upon the cards so that these two numerals on the adjacent edges, no matter how the cards are placed together, will always be in proper upright positions.

There are three face plates, each being preferably made of a single piece of rigid material, such as celluloid, and the body portion of which is indicated on the drawings by the numeral 19. The outer dimension of each is substantially the same as the outer dimension of two of the cards 18, so that this face plate may be slipped into the slotted holder from above and will extend completely across two price cards in the rear. Each face plate is formed at its central portion with a rectangular opening of such size that the two adjacent numbers on the cards in the rear of the face plate may be viewed through such opening, and all of the other numbers or printed matter upon the price card will be concealed by said face plate.

In the present instance I have provided three of these face plates. The one shown in Figures 3 and 4 has printed upon one face the symbol "c" indicating cents, at the right of the opening. On its opposite face at the left of the opening is the numeral 2, and beneath it the word "For," and at the left of the opening the symbol "c" indicating cents. The second face plate has printed upon its right side the numeral 1, and adjacent to it the word "Dollar," and on the right of the opening the symbol "c" indicating cents. On the opposite side at the left there is printed the numeral 3, and under it the word "For," and on the right of the opening the symbol "c." The third face plate has at its left the symbol "lb." indicating pounds, and on the right of the opening the symbol "c," and on its opposite face at the left there is the abbreviation "Doz," indicating dozen, and at the right the symbol "c."

In practical use, and assuming that it is desired to use the device in connection with articles that are to be sold for fifteen cents each, then the operator places the face plate, shown in Figures 3 and 4, with the face shown in Figure 3 at the front, and this face plate is then put into the slotted holder. Then he selects the price card shown in Figure 16 and puts it at the right side of the holder immediately in the rear of the face

plate. He then selects the price card shown in Figures 13 and 14, and places it with the numeral 5 adjacent to the numeral 1 in the right side of the holder, and in the rear of the face plate. Then the remaining price cards and face plates are inserted in the slot of the holder in the rear of the cards mentioned, there being just sufficient space to properly receive them and hold the face plates and cards displayed through the opening therein flush against the marginal edges 13 and 15 of the holder. Obviously any combination of numbers up to 99 may be displayed through the opening in the center of the face plate. If it is desired, however, to indicate the price per pound or dozen, or two or three articles for the price displayed through the opening in the face plate, the other face plates may be employed. Furthermore, by using the face of the face plate shown in Figure 5, the symbol "1 dollar" may be added to the numerals displayed through the opening in the face plate, thereby providing a large number of different price indicating marks.

One of the advantages of my device is that it is self-contained and a unitary structure, and those face plates or price cards that are not being displayed are contained within the holder, so that they are not likely to become lost or misplaced.

I claim as my invention:

In a device of the class described, the combination of a holder formed of sheet metal and comprising upright body portion, means for detachably connecting it to a shelf, the marginal edges of the sides and bottom of the body portion being projected first outwardly and then toward the center of the body portion to form card receiving slots 100 open at the top, four cards each being substantially rectangular in outline and of a size substantially half the size of the body portion, and being designed to rest in said slots with their adjacent edges substantially 105 in engagement with each other, said cards having marked upon their central portions the words "Right" and "Left," and also having symbols thereon near the edges thereof to indicate prices, and a face plate of a size substantially that of two of the price cards and designed to be inserted from above in said slots of the holder and to extend completely across two price cards and to retain the price cards in position in the holder, 110 said face plate being formed with a central opening and being so arranged that when in position in front of two price cards, it will conceal all of the symbols on the price cards except the two that are adjacent to the marginal edges of the price cards, which latter symbols may be viewed through the opening in the face card, for the purposes stated.

Des Moines, Iowa, June 17, 1927.
ALVIN E. COBB.
